UNITED STATES PATENT OFFICE.

FRANK EBERHART, OF NEW YORK, N. Y.

FEED-WATER HEATER.

1,151,577.

Specification of Letters Patent. Patented Aug. 31, 1915.

Application filed February 5, 1912. Serial No. 675,573.

To all whom it may concern:

Be it known that I, FRANK EBERHART, a citizen of the United States, and a resident of New York city, in the county and State of New York, have invented a certain new and useful Improvement in Feed-Water Heaters, of which the following is a specification.

My invention relates to feed water heaters or fuel economizers, and is adapted for use in connection with any heating system.

I have found that by connecting my heater or fuel economizer in a by-pass around a damper in the flue in such a way that it is necessary for the waste heat in the escaping gases to pass through the heater or economizer, many advantages result in addition to the great saving in fuel consumption. One of the advantages of my invention is that it is adapted for use in any heating system, the heater being so constructed and so connected with the system that it may be readily connected to and disconnected from the system, or may be operationally cut out temporarily. I have also found that, by dividing my heater into two compartments connected at the end opposite the connection with the flue, a proper circulation of the waste heat is obtained.

In the drawings forming a part hereof, Figure 1 is an illustration of my feed water heater or fuel economizer and its connections; Fig. 2 is a view of my fuel economizer with the door removed; Fig. 3 is a side view of Fig. 1 with the door in place taken through the center; Fig. 4 is an interior view from the top of Fig. 2 with the heating coils removed; Fig. 5 is a detail of the dividing plate; Fig. 6 is an interior view of the door; and Fig. 7 is a modification of my invention.

In the drawings, in which like numbers refer to like parts, 1 is the ordinary smoke pipe or flue leading from the fire box to the chimney, provided with dampers 4 and 5; 6 is my improved fuel economizer which is connected by pipes or flues 2 and 3 arranged as a by-pass around the damper 4 in the smoke pipe or flue 1.

My economizer 6 is preferably made of sheet metal lined on the inside with asbestos board 7 to prevent heat radiation. It may, however, be made of concrete or any suitable masonry work. The lining may be omitted, however, if it is desirable to use the economizer for heating the room in which

it is placed. I prefer to place my economizer close to the boiler, although this is not essential.

8 and 9 represent, respectively, the top 60 and bottom of the economizer.

My economizer I preferably mount upon legs 10, 10 made of angle iron, by cutting out triangular pieces and bending the angle irons, as shown in Fig. 3. The legs 10, 10 65 are connected together by an angle iron or bar 11.

To secure proper circulation of the heat in the economizer I divide the interior into two compartments 12 and 13 connected by 70 separate passages with the smoke pipe or flue and connected with each other by a passage at the ends of the compartments opposite the end when they connect with the smoke pipe or flue. For this purpose, I provide a division plate 14, which is held in place by angle irons 19, 19 arranged down the back of the economizer, angle irons 20, 20 across the top, angle irons 42, 42 on the inside of the door and by the bar 18, connected at its ends to legs 16. The angle irons 19, 19, 20, 20, 42, 42, being arranged 80 in pairs parallel to each other form slots for the division plate 14. Legs 10, 10 supporting the economizer casing are arranged 85 below legs 16 within the economizer, so as to be bolted thereto, if desired.

The coil 25 for the water to be heated, which, as shown, is an ordinary radiator, is mounted upon the legs 16, and is held in 90 place thereon by the flanges 17. The coil 25 may be arranged vertically, as shown, or horizontally if desired, and any coil of pipes or other means for holding the water to be heated may be used in place of the coil or 95 radiator shown. The dividing plate 14 is composed of three members, as shown in Figs. 3 and 5, the two smaller members being adapted to fit behind the radiator at the upper corner, and at the lower corner, and 100 provided with cut-outs 43 to register with the nipples between the coils in the radiator. The other member of the dividing plate 14 is provided with similar cut-outs 43 to register with the radiator nipples, and if so 105 formed that when the radiator has been placed in position within the casing of the economizer and the members composing the plate 14 are in position, the chamber is completely divided into two compartments so 110 that there is no connection between the compartments except the passage 45 below the

dividing plate at the bottom of the chamber, as shown in Figs. 2 and 3. The two smaller members of the dividing plate 14 are provided with small plates 22, so arranged on both sides of the plate to form a groove into which the larger member of the plate 14 will slide, while the larger member is provided with similar small plates 22^a, 22^b, forming a similar groove for the smaller members to slide into. It will be seen that by placing the two smaller members of plate 14 in their positions between the angle irons at the top, bottom and back of the casing and then placing the radiator in position on the legs 10 of the casing, and the larger member of the plate 14 may be slid into position between the coils of the radiator and will be held in position by the grooves formed by the small plates 22, 22^a, the angle irons arranged on the back 20 of the casing, and by the angle irons 42 arranged on the inner side of the door 35 of the casing, thus dividing the economizer into two compartments and separating the coil into two parts, one in each compartment. 25 The front of the casing is provided with angle irons 38, as shown in Fig. 4, bolted to the sides of the cabinet and adapted to act as a door frame. The inner side of the door 35, which is substantially the full size 30 of the casing to afford easy access for cleaning, is provided with angle irons 36 extending entirely around its inner side, and arranged so as to pass within the angle irons 38 and hold the door in position. I provide 35 clamping devices 34 for locking the door in position, preferably using wedge-shaped clamps such as are used in connection with ice-boxes, etc., for the purpose of forcing the door inward so as to make the cabinet 40 comparatively air-tight.

In order to distribute the heat throughout the compartment I provide the spreader plates 46, which I place on the top of the coil in each compartment, and these plates 46 may 45 be flat, as shown and provided with openings 47 arranged to permit the heat to come in contact with all parts of the liquid containers or may be in conical form provided with suitable openings if desired, or may be of 50 one piece of metal without any openings. This spreader is not essential in all the forms of my invention but it will be found to be advantageous in some instances, especially where the area of the compartments 55 through which the heat passes is greater than the area of the smoke pipe or flue, or the inlet pipe 2, the object of the spreader being to direct the heat into contact with the exposed surface of the coils.

60 My fuel economizer is connected with the return pipe for the water of condensation or with the feed water pipe, or both, as follows: 28 is the feed water pipe; 27 is a supply pipe connecting my fuel economizer 65 with the pipe 28. 26 is a valve placed in

the pipe 27 between the feed water or return pipe 28 and the entrance to the fuel economizer. 44 is a discharge pipe leading from the fuel economizer to the pipe 31, which leads directly to the boiler. This pipe 44 is 70 provided with a valve 32 and with a branch 33 which leads to the top of the boiler or acts as a vent, or it may be provided with a cock or be open to the atmosphere, if desired. 29 is a pipe leading from the return pipe or feed water pipe 28 to the boiler pipe 31 and adapted to act as a by pass around my economizer. This pipe 29 is provided with a valve 30.

75 My fuel economizer may be connected 80 with the supply pipe at the top of the coil and the discharge taken from the bottom if desired, as shown in Fig. 7.

In use, my fuel economizer operates as follows: The valve 29 in the pipe 30 being 85 closed, and the valves 26 and 32 in the pipes 27 and 44 respectively, being open, the device is operatively connected with the boiler. If it is desired for some reason not to use the 90 economizer the valves 26 and 32 are closed and the valve 30 open, thus permitting the water to pass directly from the return or feed water pipe 28 through the pipe 29 into the pipe 31 directly to the boiler. Assuming the fire to have been started, and the 95 valve 30 in the pipe 29 closed, the valves 26 and 32 in the pipes 27 and 44 respectively, open, and the dampers 4 and 5 open, the operation will be as follows: The damper 4 is closed, the operation of the damper 5 being 100 automatically regulated. Then the escaping gases passing through the smoke pipe or flue would, by reason of the fact that the damper 4 was closed, be compelled to pass down through the pipe 2 into the fuel 105 economizer on one side of the dividing plate through passage 45 below the dividing plate 14, up through the other compartment on the opposite side of the dividing plate, out through the pipe 3 into the flue 1, and thus 110 to the chimney. The heat in thus passing down through one side of the economizer and up the other, would be caused to circulate around through coil 25, thus heating the feed water or re-heating the water of con- 115 densation within the coil so as to supply same to the boiler in a heated condition.

120 In Fig. 7 I have shown a modification of my device in which the casing 38 is provided with doors 39 in the front and doors 40 on the bottom, held in position by means of thumb-bolts or fasteners 41, and so arranged as to be easily removed for the purpose of access to the device so as to clean same. In this form, I have shown the pipes arranged 125 in horizontal position. This form may be used without the division plate, where the area of the interior of the heater or economizer, after deducting a space occupied by the coil, is substantially the same as the 130

area of the smoke pipe or flue 2. If the area of the interior of the economizer or the heater is, after deducting the space occupied by the coils, greater than the area of the smoke pipe 2, then it will be found to be advantageous to use a similar division, and perhaps the spreader device.

What I claim is:

1. In an economizer, a casing, angle irons arranged on one side of said casing, a door adapted to form the front of said casing, and angle irons arranged on said door and adapted to coöperate with those on the front of the casing to hold the door in position. 75
2. In an economizer, a casing, angle irons arranged on one side of said casing to form a door frame, a door adapted to form the front of said casing, angle irons arranged on said door and adapted to coöperate with those on the front of the casing to hold the door in position, and means for fixedly securing said door in position.
3. In an economizer, a casing, baffle-plates adapted to divide said casing into compartments, a door adapted to form the entire front of said casing, and angle irons arranged in pairs on the inner side of said door and said casing to engage with said baffle-plates and hold the same in position. 90
4. In an economizer, a casing, baffle-plates adapted to divide said casing into compartments, a door adapted to form the entire front of said casing, angle irons arranged in pairs on said door and said casing to form grooves to accommodate, said baffle-plates and hold the same in position, and said casing having openings in the top thereof into each of said compartments. 95
5. In an economizer, angle irons arranged to form legs therefor, a tie rod connecting said legs, legs within said economizer arranged immediately above the aforesaid legs, a tie rod connecting said last-mentioned legs, and a water container mounted on said legs.
6. A heat-interchanging device comprising a casing, fluid-conducting coils therein, pipes connecting said coils, and means separating said casing into compartments, comprising a plurality of members having cut-away portions to fit around said pipes, said members all coöperating together to form a complete partition between said compartments. 105
7. A heat-interchanging device, comprising a casing adapted to conduct a heat-conveying medium longitudinally therethrough, a fluid-conducting coil therein comprising a plurality of units extending longitudinally of the casing and being spaced to provide unobstructed passages from one end of the casing to the other end thereof between their longitudinal faces, baffles coöperating with said units to cause a uniform flow of heat-conveying medium therebetween. 120
8. In an economizer, a casing having a partition therein extending from the top to a point near the bottom thereof and forming longitudinal passages therein, fluid coils for said passages extending from the top of the casing to a point above the bottom of said partition, the coils having longitudinal faces parallel to each other and spaced to provide unobstructed passages between them and longitudinally of the casing, and means for conducting heated gas to the top of one 125 passage and from the top of the other.
9. In an economizer, a casing having an opening in one side, angle irons on said casing around the edges of the opening and a door for said opening, angle irons arranged on said door and adapted to coöperate with the angle irons on said casing to hold the door in said opening, angle irons attached to the wall of the casing opposite the wall having the opening therein and spaced to form a groove, angle irons attached to the door and spaced to form a groove, a partition positioned in and held by said grooves and extending from the top of the casing to a point near the bottom thereof and forming two passages therein, fluid coils in said passages, means to support said coils and said partition, and means for conducting heated gas 130 to the top of one of said passages and from the top of the other passage.
10. In an economizer, a casing, a supporting frame for the casing, supports within said casing and resting on the bottom thereof, fluid coils having legs resting on said supports and having parallel vertical faces forming unobstructed vertical passages therebetween, a tie rod connecting said supports, a partition dividing said casing into vertical passages and supported by said tie rod and extending therefrom between certain faces of said coils to the top of said casing, means for conducting heated gases to the top of one passage and from the top of the other. 135
11. In an economizer, a casing having an opening in one side, a door for said opening, angle irons attached to the wall of the casing opposite the wall having the opening therein and spaced to form a groove, angle irons attached to the top of said casing and spaced to form a groove, angle irons attached to the door and spaced to form a groove, a partition positioned in and held by said grooves and extending from the top of the casing to a point near the bottom thereof and forming two passages therein, fluid coils in said passages, means to support said coils and said partition, and means for conducting heated gas to the top of one of said passages and from the top of the other passage. 140
12. In an economizer, a casing, supporting legs therein for a fluid coil, a fluid coil sup-

ported by and spaced above said legs, a partition extending between certain faces of said coil from the top of the casing down to the level of the tops of and being supported from said legs, and means for conducting heated gas to the casing at one side of said partition and from said casing at the other side of said partition.

In testimony whereof, I have signed my name to this specification, in the presence of ~~10~~ two subscribing witnesses.

FRANK EBERHART.
